UNITED STATES PATENT OFFICE.

MAXMILIAN ERNST, OF CLEVELAND, OHIO.

DESIGN FOR A FOOT-WARMER.

SPECIFICATION forming part of Design No. 26,007, dated September 8, 1896.

Application filed December 3, 1895. Serial No. 570,958. Term of patent 3½ years.

To all whom it may concern:

Be it known that I, MAXMILIAN ERNST, a citizen of the United States, residing at Cleveland, in the county of Cuyahoga and State of Ohio, have invented and produced a new and original Design for Foot-Warmers and Foot-Stools, of which the following is a specification, reference being had to the accompanying drawings, forming a part thereof.

Fig. 1 is a view in perspective of a foot-warmer and foot-stool possessing my design. Fig. 2 is a central longitudinal section, and shows in plain elevation the two handles provided at opposite ends, respectively, of the receptacle. Fig. 3 is a transverse section on any one of lines 3 3, Fig. 2.

The leading feature of my design consists in the shape of the earthen receptacle, which is oblong, flat at the bottom, semicircular or convex at the top in end elevation, and having ridges or flanges exteriorly and extending transversely of the top and sides of the receptacle and arranged at suitable intervals to form two parallel panels extending over the sides and top of the receptacle.

Referring to the drawings, A designates the chamber of the oblong earthen receptacle, whose bottom A' is flat and whose top in end elevation is semicircular or convex.

Three flanges or ridges A², A², and A⁴ are formed exteriorly of the receptacle and extend transversely of the top and sides of the receptacle and somewhat below the sides to form feet A⁵ for the receptacle. Ridge or flange A⁴ is located at the central portion of the device, and the two flanges or ridges A² A² are located at opposite ends, respectively, of the device, and hence two panels A³ A⁵, adapted to be engaged by the person's feet in the operation of the device, are formed between the central flange or ridge A⁴ and the end ridges or flanges A² A².

A device of the character indicated, having two panels formed externally thereof and extending transversely of the top and sides of the receptacle, is not only exceedingly convenient, but possesses a desirable appearance.

What I claim is—

The design for a foot-warmer, substantially as herein shown and described.

In testimony whereof I sign this specification, in the presence of two witnesses, this 26th day of November, 1895.

MAXMILIAN ERNST.
